UNITED STATES PATENT OFFICE.

ALBERT J. CHARLTON, OF LOWDEN, IOWA.

CONDENSER.

Application filed August 14, 1922. Serial No. 581,787.

To all whom it may concern:

Be it known that ALBERT J. CHARLTON, a citizen of the United States, residing at Lowden, in the county of Cedar and State 5 of Iowa, has invented certain new and useful Improvements in Condensers, of which the following is a specification.

My invention relates to an article of manufacture comprising a combined condenser, 10 heat and water gauge for automobiles.

The objects of my invention are, 1st, to provide, as an article of manufacture, an attractive-looking radiator cap containing means for condensing the steam and vapors 15 from automobile radiators and means for easily and quickly determining the temperature and quantity of water within a radiator; 2nd, to provide as an article of manufacture, a radiator cap containing a movable 20 element which indicates both the level and temperature of the cooling medium in the radiator.

I attain these objects by the means illustrated in the accompanying drawings, in 25 which,—

Figure 1 is a side elevation of my device; Fig. 2 is a vertical section on the middle line of the apparatus; Fig. 3 is an enlarged cross section on the line 3—3 of Figure 1; 30 Fig. 4 is a detail showing the construction of the fixed tube; Fig. 5 is a detail showing the arrangement of the floating tube and Figure 6 is a detail showing one of the guide washers.

Similar numerals refer to similar parts 35 throughout the several views.

My device is calculated to take the place of an automobile radiator cap and has a threaded portion, 7^a, adapted to screw into 40 the throat of the radiator, 9. The body of my device comprises a casing, 7, having hollow arms, 7^b, formed integral therewith and extending therefrom radially but inclined slightly upward as they extend outward 45 from the body.

Openings, 14, are left at the front and rear of the body which is preferably of thin metal. A glass tube, 6, is secured inside of 50 the body, 7, and may be secured in place by a packing washer at each end or any suitable means to prevent breakage.

Openings, 11, are left in the sides of the glass tube, 6, to allow free communication 55 between the interior of the arms, 7^b, and the chamber formed by the glass tube, 6.

A fixed tube, 4, is formed integral with a

head, 4^a. The flanges of the head, 4^a, extend downwardly and fit closely upon the upper end of the body, 7. Spring clips, 12, are secured to the head, 4^a, and are locked in position by pins, 13, secured to the body, 7, and extend into suitable openings formed in the clips 12. The tube, 4, has a perforated bottom, 4^c, which affords entrance and exit for the water of the radiator into and out of the tube, 4. The tube, 4, is shown shortened in Figure 2 and may extend into the radiator to any desired depth.

A float, 2^c, is mounted inside of the tube, 4, and is provided with guide lugs, 2^b, secured thereto which travel in corresponding channels formed on opposite sides of the tube, 4, to keep the float, 2, from turning around in the tube, 4.

The tube, 4, is preferably made of metal 75 and is provided with openings, 4^b at the front and rear thereof which register with the openings, 14, in the body, 7.

Secured to the float, 2^c, is a smaller tube, 2, extending upwardly from the float and 80 having longitudinal ribs, 2^a, extending laterally therefrom. These ribs travel in notches, 8^a, in the guide washer, 8, and assist in preventing the tube, 2, from turning. A thermometer, 1, is secured within the float and 85 its lower end rests upon a suitable cushion, 10, which is preferably perforated.

A tube, 2, is provided with openings at 90 each side which register with the openings, 4^b, and 14.

A thermometer, 1, is preferably a triangular magnifying thermometer and arranged so that it can be read either from the front or rear.

The guide washer, 8, is secured near the 95 middle of the tube, 4, which is preferably grooved as at 4^c, to secure the guide washer in position.

The tube, 5, represents the ordinary vent or overflow tube of the radiator which is 100 lengthened and extended upwardly and flattened so as to enter the chamber between the tubes 4 and 6.

In the operation of my device the body, 7, is screwed into the throat of the radiator 105 as shown in Figure 2. The tube, 4, is then inserted within the body and the head, 4^a, secured in place by the spring clips, 12. The tube, 4, contains the float and thermometer. The radiator, of course, is filled to the desired height before the tube, 4, is inserted.

When the tube, 4, is inserted, the water en-

ters the lower end of the tube and acting upon the float, 2, carries it upwardly so that the top of the tube, 2, reaches the top of the sight, 14.

5 As the engine is operated and the water becomes heated, the heat is transmitted to the thermometer which is preferably provided with a red liquid for an expansion medium. The thermometer then indicates the 10 temperature of the water and the height of the tube, 2, indicates the height or quantity of the water in the radiator.

15 As the water in the radiator becomes hotter, the steam enters the chamber formed by the tubes, 4 and 6, and also enters the interior of the arms, 7^b, and as it is cooled, the condensation water runs back into the radiator and thus avoids escape of the cooling medium.

20 Under ordinary conditions, my device will cause sufficient condensation to prevent the escape of steam through the outlet pipe, 5. In extreme cases, where the water is heated to such an extent that it rises above the 25 top of the outlet pipe, 5, the water can flow off through the outlet, 5. I have not shown the body of the radiator nor the outlet, 5, extending through the radiator, but such devices are in common use and well-known.

30 It is well known that with heat indicating devices now in use, the water in the radiator may become so low as to endanger the safety of the engine without the driver being able to tell whether the heat is due to 35 low water or to some other condition. My device obviates this difficulty, as the driver can see at a glance whenever the water is below a given level, for the thermometer and tube carrying it will drop entirely out of 40 sight when such a condition arises.

When the radiator is filled to the proper level, the top of the thermometer will stand at the top of the float chamber. It is obvious that when the radiator is filled to the 45 prescribed height, if the cooling medium

has a specific gravity less than that of water, the thermometer and float will stand at a correspondingly lower level. My device will thus act as a gauge to indicate the specific gravity of the cooling medium. If desired, 50 a scale may be attached to the float chamber to indicate the specific gravity.

I claim:

1. As an article of manufacture, a radiator cap having a neck adapted to seat upon the 55 throat of the radiator, a cylindrical body formed integral with or suitably secured thereto and hollow arms extending outward radially from the body, the body and arms constituting a continuous condensation 60 chamber.

2. A combined radiator cap and condenser comprising a neck adapted to seat upon the throat of the radiator, an enlarged hollow body secured to and extending above the 65 neck, and a plurality of hollow arms united to and extending outwardly from the body and sloping downwardly toward the body.

3. As an article of manufacture, a radiator cap having a neck adapted to seat upon the 70 throat of the radiator, a cylindrical body formed integral with or suitably secured thereto and hollow arms extending outward radially from the body and sloping downwardly toward the body, the body and arms 75 constituting a continuous condensation chamber.

4. As an article of manufacture, a radiator cap having a neck adapted to seat upon the 80 throat of the radiator, a cylindrical body formed integral with or suitably secured thereto and hollow arms extending outward radially from the body, the bottom portion of the hollow arms sloping downwardly toward the body and the body and arms 85 constituting a continuous condensation chamber.

In testimony whereof I affix my signature.

ALBERT J. CHARLTON.
